DESIGN FOR A VENTURI MIXING CHAMBER FOR LIQUID FUEL BURNERS

Styles T. Howard, Jeffersonville, Ind.

Application August 9, 1941, Serial No. 102,776

Term of patent 3½ years

To all whom it may concern:

Be it known that I, Styles T. Howard, a citizen of the United States, residing at Jeffersonville, in the county of Clark and State of Indiana, have invented a new, original, and ornamental Design for a Venturi Mixing Chamber for Liquid Fuel Burners, of which the following is a specification, reference being had to the accompanying drawing, forming part thereof.

Fig. 1 is a perspective view of a Venturi mixing

chamber for liquid fuel burners showing my new design.

Fig. 2 is a longitudinal sectional view on line 2—2 of Fig. 1; and

Fig. 3 is a cross-sectional view on the line 3—3 of Fig. 1.

I claim:

The ornamental design for a Venturi mixing chamber for liquid fuel burners, as shown.

STYLES T. HOWARD.
